UNITED STATES PATENT OFFICE.

JOHN HENRY COGSWELL, OF LANSING, MICHIGAN.

ATOMIZER FOR INTERNAL-COMBUSTION ENGINES.

1,291,767.

Specification of Letters Patent. Patented Jan. 21, 1919.

Application filed May 16, 1918. Serial No. 234,947.

To all whom it may concern:

Be it known that I, JOHN H. COGSWELL, a citizen of the United States, residing at Lansing, in the county of Ingham and State 5 of Michigan, have invented certain new and useful Improvements in Atomizers for Internal-Combustion Engines, of which the following is a specification, reference being had therein to the accompanying drawing.

This invention relates to new and useful improvements in automatic atomizers for internal combustion engines and the object in view is to produce a simple and efficient device of this nature which may be easily and 15 quickly attached to the manifold of an engine and adapted to admit air, proportionate to the quantity of fuel passing through the manifold to the engine.

The present invention consists of a simple 20 device of this nature which will be automatic in its action and serve to thoroughly mix the gas and air before entering the combustion cylinder, thus economizing in fuel and serving to reduce to a minimum the deposit 25 of carbon on the inner surface of the cylinder.

My invention is illustrated in the accompanying drawings, in which:—

Figure 1 is a sectional view showing the 30 same as applied to a manifold.

Fig. 2 is an enlarged central sectional view through the device.

Fig. 3 is a sectional view on line 3—3 of Fig. 2.

Fig. 4 is an end view of the atomizer, and 35 Fig. 5 is a detailed sectional view of a modification of my invention.

Reference now being had to the details of the drawings by letter, A designates the shell 40 of the atomizer having a circumferential, angular shoulder B near one end for a wrench hold and the one end of the shell is circumferentially threaded as at C and adapted to engage the threads D formed in 45 the marginal edge of the opening in the manifold E. Said shell, which is cylindrical shaped, has circumferential threads F at one end and H is an interiorly threaded cap fitted over said circumferential threads of the 50 shell and the end of the cap has its inner surface conically shaped and tapering to a point, and K designate ducts through which the air is allowed to enter the shell. A valve

N, of cylindrical form, is mounted within the shell and has a conically shaped end O, 55 conforming to the taper on the inner face of the cap and the conical portion of the valve is adapted to form a part to regulate the passage of air through the ducts K. Said valve is longitudinally channelled as at L, and R is 60 a coiled spring which is mounted within the shell bearing against the bottom of the latter about the duct T leading through the inner threaded end and the outer end of said springs bear against the valve N and normally holds the same against the cap in the manner shown. The purpose of said spring is to normally hold the outer end of the valve in closed relation with the duct K and the tension of said spring may be adjusted 70 by the position the cap assumes upon the threaded portion of the shell. For instance, if it is desired to increase the tension of the spring, causing a greater suction to be required to actuate the valve to permit air to 75 enter, the cap is screwed farther toward the manifold than would otherwise be the case, the unscrewing of the cap tending to lessen the tension of the spring.

In operation, the device is applied to the 80 manifold or to the pipe or opening between the carburetor and the bore of the cylinder and, when the engine is in operation, the suction upon the manifold as it overcomes the tension of the spring will cause the valve to 85 unseat and draw in air in sufficient quantity to thoroughly atomize the fuel with which it becomes mixed before entering the combustion cylinder.

By the provision of a device embodying 90 the features of my invention, I have found that the thorough mixing of the fuel with air will tend to reduce to a minimum the deposit of carbon upon the cylinder and piston and serve as a means for economizing in 95 fuel.

What I claim to be new is:—

An atomizer for internal combustion engines, comprising a shell adapted to be attached to the manifold of an engine, and 100 having a chambered portion, the inner portion of which is contracted, said chamber having an annular shoulder, a hollow cylindrical valve with its outer end conical shaped and provided with apertures therein, 105 an adjustable cap interiorly threaded and

fitted over the threaded portion of said shell, the outer end of the cap having a tapering portion over the tapering portion of the valve only and with which it conforms, said cap having apertures at the inner end of the tapering portion thereof, a spring within the chambered portion of the shell and bearing against said shoulder and the inner end of

the valve, and a jam nut upon the threaded circumference of the shell.

In testimony whereof I hereunto affix my signature in presence of two witnesses.

JOHN HENRY COGSWELL.
